UNITED STATES PATENT OFFICE.

RALEIGH RAYMOND OLDHAM, OF LAUREL, WASHINGTON.

KNOCKDOWN TOOTH-BRUSH.

1,216,159.

Specification of Letters Patent. Patented Feb. 13, 1917.

Application filed June 30, 1916. Serial No. 108,895.

To all whom it may concern:

Be it known that I, RALEIGH RAYMOND OLDHAM, a citizen of the United States, residing at Laurel, in the county of Klickitat, 5 State of Washington, have invented a new and useful Knockdown Tooth-Brush; and I do hereby declare the following to be a full, clear, and exact description of the invention, such as will enable others skilled in the art 10 to which it appertains to make and use the same.

The present invention relates to a tooth brush, and has for its object to provide a device of this character which embodies 15 novel features of construction whereby it can be readily knocked down and packed in a small amount of space when not in use, thereby enabling it to be conveniently carried when traveling.

20 Further objects of the invention are to provide a device of this character which is comparatively simple and inexpensive in its construction, which can be easily taken apart or put together, which presents a rigid 25 construction when put together and ready for use, and which can be easily kept in a clean and sanitary condition.

With these and other objects in view, the invention consists in certain novel combinations and arrangements of the parts as will 30 more fully appear as the description proceeds, the novel features thereof being pointed out in the appended claims.

For a full understanding of the invention, 35 reference is to be had to the following description and accompanying drawing, in which:—

Figure 1 is a side elevation of the head end of the tooth brush.

40 Fig. 2 is a similar view of the handle end thereof.

Fig. 3 is a top plan view of the head end of the tooth brush.

Fig. 4 is a similar view of the handle end 45 thereof.

Fig. 5 is a longitudinal sectional view through the tooth brush, the parts thereof being assembled in operative position.

Fig. 6 is an enlarged transverse sectional 50 view on the line 6—6 of Fig. 5.

Fig. 7 is a longitudinal sectional view through the carrying case within which the brush is packed when knocked down.

Corresponding and like parts are referred 55 to in the following description and indi-

cated in all the views of the drawing by the same reference characters.

Specifically describing the knock down tooth brush, the numeral 1 designates the brush head upon which the bristles 2 may 60 be mounted in any conventional manner. A hollow stem 3 projects rearwardly from the brush head 1, said stem being formed of resilient sheet metal, and being provided upon one side thereof with a longitudinal slit 4. 65 The free end of the hollow stem 3 is preferably slightly tapered, as indicated at 3^a, so that the stem can be readily telescoped within a tubular socket 5 at one end of the handle 6. The socket and handle may be 70 conveniently formed by rolling a piece of sheet material, the socket having a longitudinal slit 7 extending from end to end thereof, and the handle 6 being reduced at the rear end of the socket 5 on the side 75 thereof provided with the slit 7, thereby providing a stop shoulder which limits the inward movement of the hollow stem 3 within the socket. In forming this shoulder, the edges of the rolled piece of sheet 80 metal from which the handle member is formed may have lateral cuts 8 therein, the edges of the sheet metal overlapping each other at the handle of the device, and being spaced to provide the slit 7 at one side of the 85 socket 5. A longitudinal flange 9 projects inwardly from one of the edges of the slit 7, the rear end of the flange being severed from the edge of the slit to provide a spring 90 tongue 10 which projects rearwardly a slight distance over the handle 6 so that it can be readily engaged by the fingers of the hand and flexed laterally in either direction.

The hollow stem 3 of the brush head 1 is 95 designed to telescope within the socket 5 of the handle 6, the flange 9 being received within the slit 4 of the stem 3 to lock the brush head and handle against relative rotation and cause the parts to always be assembled in the same relation to each other, and the inherent resiliency of the stem and socket causing them to frictionally engage each other, so that a tight fit is assured. One of the edges of the slit 4 of the hollow 100 stem 3 may be provided at a point toward the outer end thereof with a projection 11 adapted to enter an opening 12 in the spring tongue 10 when the stem is forced home in the socket, thereby preventing the members 105 from being accidentally pulled apart. In 110

order to separate the members, however, it is merely necessary to press against the projecting end of the spring tongue 10 with one of the fingers of the hand and flex the same a sufficient amount to disengage the projection 11 from the opening 12 of the spring tongue, and then forcibly pull the members apart. The tooth brush can be packed in a very small amount of space when knocked down, thereby enabling it to be carried without annoyance or difficulty.

If desired, the knocked down tooth brush may be packed in the end chamber A of a tubular carrying case 13, said case being provided at the ends thereof with removable caps 14, and being subdivided by the intermediate partition 15 into the end chambers A and B, respectively. The end chamber A may receive the knocked down tooth brush, while the end chamber B is adapted to receive a box or container 16 filled with some form of tooth cleaning preparation. This tubular case 13 occupies but a small amount of space and constitutes a very convenient means for carrying the tooth brush and dentifrice.

Having thus described the invention, what I claim as new and desire to secure by Letters Patent, is:—

30 1. A knock down tooth brush including a head, a hollow stem projecting from the head and having a slit in one side thereof, a handle, a socket at one end of the handle, and a longitudinal flange projecting within the socket, the stem of the brush head being adapted to telescope within the socket of the handle and the longitudinal flange of the socket being received within the slit of the stem to hold the parts against relative rotation.

35 2. A knock down tooth brush including a head, a hollow stem projecting from the

head and having a slit in one side thereof, a handle, a socket at one end of the handle, a longitudinal flange projecting within the 45 socket, a spring tongue at one end of the socket, the extremity of the tongue projecting beyond the socket so that the tongue can be easily flexed, the stem of the brush head being adapted to telescope within the 50 socket of the handle and the longitudinal flange of the socket being received within the slit of the stem, and means upon the stem for interlocking with the resilient tongue to lock the members together. 55

3. A knock down tooth brush including a head, a hollow stem projecting from the head and having a slit in one side thereof, a handle, a socket at one end of the handle, said socket having a slit in one side thereof 60 and the handle being flattened at the base of the socket, a longitudinal flange projecting within the socket from one of the edges of the slit in the side thereof, a spring tongue arranged at the rear end of the 65 flange and projecting through the base of the socket and over the handle so that it can be readily flexed by the fingers, the stem of the brush head being adapted to telescope within the socket of the handle and the longitudinal flange of the socket being received within the slit of the stem, and a projection 70 upon one of the edges of the slit in the stem for obtaining an interlocking engagement with the resilient tongue to lock the two 75 members together.

In testimony whereof I have signed my name to this specification in the presence of two subscribing witnesses.

RALEIGH RAYMOND OLDHAM.
